ABSTRACT

A hopper car having a continuous discharge opening and including a transversely sliding hopper discharge gate suspended on a hanger having rollers moving on support beams in transverse tubular type hoods to provide for smooth movement of the gate. An operating screw, the hanger member, and the support beams are positioned under cross ridge hoods which connect longitudinally extending side slope sheets to thereby provide a concealed operating mechanism and eliminate the need for intermediate transversely extending slope sheets.

FIG. 5

RAILWAY HOPPER CAR CLOSURE ACTUATING MECHANISM

BACKGROUND OF THE INVENTION

1. Field of the Invention

This invention relates to railway hopper car sliding discharge gates.

2. Description of the Prior Art

The prior art hopper discharge mechanisms employed on hopper gates are generally positioned under the intermediate transversely extending slope sheets of the hopper and thereby eliminate an area of the car which could contain additional volume for a hopper. The present invention provides a compact operating mechanism for a large sliding gate which permits the entire bottom portion of a hopper to be available for rapid discharge of lading.

SUMMARY

This invention relates to a hopper discharge door operating mechanism and in particular to a mechanism employed to actuate sliding discharge doors. The invention comprises a sliding door having a hanger member with rollers mounted thereon for suspending each door on a pair of transversely extending beam members. The hanger member also includes an acme or machine threaded portion into which a rotating acme or machine threaded shaft is positioned to provide for sliding movement of the door upon rotation of the threaded shaft.

It is an object of the present invention to provide a sliding door operating arrangement which is compact and fits on a hopper device without subtracting materially from the volume of the hopper.

Also it is an object of the present invention to provide a sliding hopper discharge door suspended on a track means which is supported between slope sheets of the hopper device.

It is yet another object of the present invention to provide a sliding hopper discharge gate arrangement to a railway hopper car without the use of intermediate transversely extending slope sheets which provide a mounting area for the door operating mechanism.

Another object of the present invention is to provide a railway hopper car having a continuous trough shaped hopper discharge opening having only end and side slope sheets for directing lading into the discharge opening.

These and other objects of the invention will become apparent from reference to the following description, attached drawings and appended claims.

BRIEF DESCRIPTION OF THE DRAWINGS

FIG. 1 is a side elevational view of a railway hopper vehicle employing the sliding discharge gate operating mechanism of the present invention;

FIG. 2 is a top plan cross sectional view taken generally along lines 2-2 of FIG. 1;

FIG. 3 is a cross section view taken generally along lines 3-3 of FIG. 2;

FIG. 4 is a sectional view of the intermediate and end gate mounting arrangement illustrated in FIG. 1;

FIG. 5 is a cross sectional view taken along lines 5-5 of FIG. 2;

FIG. 6 is a modification of the gate mounting arrangement illustrated in FIG. 5; and

FIG. 7 is a view of a reinforced sliding door.

DESCRIPTION OF THE PREFERRED EMBODIMENT

FIG. 1 discloses a typical railway hopper car 10 which employs the sliding discharge gate operating mechanism of the present invention. The hopper car 10 includes the usual pair of spaced reinforced side wall units 12 joined by a roof and hatch cover unit 14 which extend between the end bulkheads 16. A pair of intermediate bulkheads 18 having door support flanges 19 at their lower portions form the intermediate walls of spaced hoppers which are contained on the hopper car 10. Transversely extending end slope sheets 20 extend downwardly away from the end bulkheads 16 to direct lading towards the hopper discharge openings. Each end slope sheet 20 includes a lower flange portion 21 which is used to mount and support the sliding gates 24.

Gate operating mechanisms are designated generally by the numeral 26 and are positioned transversely of the hopper vehicle and encased in a shroud tubular housing 28 which extends between the side slope sheets 30 of each hopper. The housing 28 is of inverted U-shaped configuration open at its lowermost portion. A pair of fabricated or rolled support beams 32 are also fixedly attached, generally welded, to the side slope sheets 30 to provide a rigid mounting and moving support member for the sliding gate 24. Each support beam 32 includes a runner portion 34 which is contoured to provide a more efficient guide surface. Beams 32 are slightly spaced from the sliding gate 24 to permit unobstructed reciprocating movement of the gate 24 during opening and closing.

The shaft support and mounting plates 36 are positioned between the support beams 32 to provide a rigid mounting point for the thrust nut 38. A hanger 40 is fixedly attached to the sliding gate by suitable fasteners or by a weld and includes a threaded portion 41 into which is fitted the threaded operating shaft 42. Guide rollers 44 are rotatably positioned atop the hanger 40 and are guided in the runners 34 of the support 32 during transverse movement of the sliding gate 24.

The exposed end portion of the operating shaft 42 have a nut portion or capstan 46 with a suitable cross section to receive a drive wrench to provide for powered opening of the sliding gates 24. The end portion of the shaft 42 is also mounted in a thrust collar 48 which resists axial loads and yet permits free rotation of the operating shaft 42. A support and mounting bracket 50 extends downwardly and then inwardly to provide a rigid support member for the exposed end portion of the shaft 42.

The mounting of the sliding door 24 will be made with reference to the illustrations in FIGS. 4, 5, and 6. As illustrated in FIG. 5 the doors are sandwiched between a top retainer member 52 and a lower support block 54. The support block 54 may contain a fiber or other type of insert 56 to provide a low coefficient of friction between the sliding doors 24 and their support blocks.

An alternate mounting arrangement is illustrated in FIG. 6 and provides a retainer 58 having a plurality of openings which contain ball or roller bearings 60 to thereby provide a rolling friction type of contact between the sliding gates 24 and their supporting members.

An alternate form of the sliding gates 24 is illustrated in FIG. 7 which discloses a reinforcing member 62 positioned on the underside of the sliding gates 24. It is contemplated that this stiffener 62 would be utilized in extremely wide doors which would tend to deflect excessively under the transport of dense and heavy lading in the hoppers. The stiffener 62 has a T-shaped cross section comprising a vertically extending web and a horizontally extending bottom flange.

THE OPERATION

As pointed out earlier, the discharge opening 22 is a continuous trough shaped opening which exposes the entire bottom of the hopper area for rapid discharge of lading. The only interruption in the complete bottom discharge opening are the transversely extending shrouds 28 which cover the operating mechanisms 26.

In operation of the sliding discharge gates 24 the capstan or nut 46 of the shaft is engaged by suitable manual or powered turning. Rotation of the capstan 46 in one direction causes the door or sliding gates 24 to open and move outwardly towards the door operator. Reverse rotation of shaft 42 closes the discharge gates 24.

To provide a smoothly opening and closing gate the present invention provides a pair of guide support rollers 44 which are positioned in the dish shaped runners 34 of the twin support beams 33.

The transversely extending side edges of the sliding gates 24 are supported in horizontally extending flanges 19, 21 of the intermediate bulkheads 18 and the slope support sheets 20 respectively. To permit easy sliding movement of these edge portions the support flanges 19 and 21 may include the support block 54 illustrated in FIG. 5 or the support assembly illustrated in FIG. 6. FIG. 5 discloses support blocks 54 fixedly secured to the support flange 19 and having a compatible insert contained therein to provide a low coefficient of slide friction in sliding gate 24. At present a fiber or other nonmetallic type of insert is contemplated.

FIG. 6 illustrates an alternate device for providing a smooth sliding gate 24 and includes a retainer 58 fixedly secured to the door support flange 19 and spaced therefrom. The retainer 58 includes a plurality of spaced openings through which are inserted the ball bearing members 60.

Thus it has been described how the sliding discharge gate arrangement of the present invention provides maximum utilization of the hopper car volume for the transport of lading by providing a door operating mechanism which is compact and fits conveniently onto the railway hopper car. By supporting the discharge gates in the central portion by a pair of transversely extending beam members 32 the edges of the discharge gate are not the sole support members for the gate and do not receive the sole force of the lading which rests above the discharge gates 24. Thus the sealing problem and binding which commonly result from prohibitively high sliding friction forces caused by high normal forces on the door support edges in ordinary sliding discharge gates is not present since the bearing edges of the gate are not as heavily loaded as is generally present in the railway industry. By removing the normal or vertical load from the edges of the discharge gates and placing loading on the support hanger 40 the sliding frictional force which resists the door opening effort of

the rotating shaft is decreased significantly and enables the mechanism of the present invention to provide a highly efficient and reliable sliding discharge gate.

The foregoing description and drawings merely explain and illustrate the invention and the invention is not limited thereto, except insofar as the appended claims are so limited, as those skilled in the art who have the disclosure before them will be able to make modifications and variations therein without departing

10 from the scope of the invention.

What is claimed is:

1. A railway hopper car having a plurality of hoppers for storage of lading and said car having intermediate bulkheads and end bulkheads, and longitudinally extending said slope sheets converging to define a generally continuous discharge opening for removing lading from within said hoppers and said discharge opening extending generally between end slope sheets and a plurality of sliding discharge door means positioned beneath each hopper and having a door operating mechanism to provide for reciprocating opening and closing movement of the door means, and the improvement comprising:

a tubular housing supported within each said hopper and extending horizontally between said side slope sheets;

said door operating mechanism being supported within said housing and including, door support beam means extending transversely of said hopper car and positioned within said housing;

a door hanger member fixedly attached to said door means substantially centrally thereof;

said door hanger member including roller support means mounted on said support beam means to permit rolling opening and closing movement of said discharge door means;

a rotatable operator means within said housing connected to said door hanger member and being accessible and operative from without said housing for opening and closing movement of said discharge door means.

2. The invention according to claim 1, and:

said rotatable operator means being a rotatable threaded shaft;

said door hanger member including a threaded nut portion receiving said threaded shaft to thereby convert rotatable movement of said shaft into transverse horizontal movement of said discharge door means.

3. The invention according to claim 1, and:

said door means having side edge portions extending transversely of the hopper car and being spaced from said centrally disposed door hanger member;

door support flanges positioned at the lower portion of the end slope sheets and at the lower portion of the intermediate bulkheads to provide a vertical support surface force to the side edge portions of said discharge door means; and,

a low friction insert mounted adjacent said support flanges and engageable with the side edge portions of the hopper doors to provide a low friction contacting and support surface.

4. The invention according to claim 3, and:

said door support means including a support block having a fiber insert contained therein.

5. The invention according to claim 3, and:
perforated retainer means mounted adjacent the
door support flange and containing a plurality of
ball bearing members contained therein and en-
gageable with the sliding gates to thereby provide 5
easily operated discharge door means.

6. The invention according to claim 1, and:
a stiffener member fixedly attached to the under side
of said discharge door means and including a main
body or web portion and having attached thereto 10
a top flange reinforcing portion.

7. The invention according to claim 1, and:
said housing having end portions attached to said lon-
gitudinally extending side slope sheets,
said housing having a lower elongated opening 15
through which said hanger member projects.

8. A railway hopper car having a plurality of adjacent
hoppers for storage of lading during transport and hav-
ing side bottom slope sheets extending longitudinally of
the car and end slope sheets for directing lading toward 20
a generally continuous discharge opening, and sliding
discharge door means mounted for reciprocating
movement across the discharge opening, a door operat-
ing mechanism including:

a tubular housing supported within each hopper and 25
extending horizontally between said side slope
sheets, said housing having a bottom elongated
opening;

transversely positioned support beam means extend-
ing within said housing between the side bottom
slope sheets;

a door hanger member projecting through said open-
ing being fixedly attached to the door means and
mounted for operative movement on the support
beam means;

guide rollers for mounting the hanger member on the
support beam means for guided movement
thereon;

rotatable shaft means operatively connected with the
door hanger member to thereby provide recipro-
cating movement of the gate means.

9. The invention according to claim 8, and:
said gate means having side edge portions extending
transversely of the hopper car;

side edge portion support means attached to the hop-
per car and having inserts to provide a low friction
support surface for the edge portions of the gate
means.

10. The invention according to claim 8, and:
said support beam means comprising two support
members having runner guide rail portions for re-
ceiving said guide rollers and suspend the door
hanger member between each of the two support
members.
